UNITED STATES PATENT OFFICE.

WILLIAM A. DOREY, OF NEWARK, OHIO, ASSIGNOR TO HOLOPHANE GLASS CO. INC.,
OF NEW YORK, N. Y., A CORPORATION OF NEW JERSEY.

DESIGN FOR A PRISMATIC GLASS GLOBE.

Application filed July 6, 1921. Serial No. 482,851. Term of patent 14 years.

To all whom it may concern:

Be it known that I, WILLIAM A. DOREY, a citizen of the United States, residing at Newark, in the county of Licking and State of Ohio, have invented a new, original, and ornamental Design for Prismatic Glass Globes, of which the following is a specification, reference being had to the accom-

panying drawing, forming a part thereof. The figure is a side view of a globe, showing my new design.

I claim:

The ornamental design for a prismatic glass globe, as shown.

WILLIAM A. DOREY.
